8 Claims. (Cl. 77—7)

This invention relates to portable power tools of the gun type having a barrel portion accommodating a motor, an implement-carrying chuck and a handle portion extending downwardly and rearwardly from said barrel portion at an obtuse angle. One object of the invention is to provide a body for a portable power tool which fits a hand holding the tool and producing an axial pressure in the direction of the axis of the barrel. Another object of the invention is to provide a body for a tool having a large rear surface on which pressure may be exerted by a hand holding the tool. Another object of the invention is to provide a body for a portable power tool of the type described which is cheap in manufacture and fits into the hand of an operator in a manner which requires little effort. A further object of the invention is to provide a body for a tool of the above mentioned type in which the feeding of the tool towards the article to be operated on may be carried out without subjecting the hand holding the tool to a bending moment or which subjects the hand or wrist to a very small moment in the two main planes of movement of the wrist. A still further object of the invention is to provide a body for a tool of the type described in which the twisting moment of a motor provided in the tool body is taken up by the hand holding the tool with as little strain as possible. A still further object of the invention is to provide a tool in which the thumb and forefinger are used together for guiding the tool towards the work and the other fingers are used for manipulation of the trigger or its equivalent. A still further object of the invention is to provide a body for a tool of the type described in which a rotary motor and speed reduction gear may be assembled into the tool body from the front end of the body. A further object of the invention is to provide a body for a tool of the type described in which ample space is provided for exhaust silencing means and in which the exhaust air from an air motor is expelled in such a manner that it does not interfere with the hand holding the tool. A still further object of the invention is to provide a tool of the type described in which the manipulation of controlling means for the tool motor has very little tendency to change the direction in which the tool is held. A still further object of the invention is to provide a tool which when lying on a table is easy to grasp with one hand in such a way that the operator immediately obtains the correct grip for operation of the tool.

For the above and other purposes we provide a body for a portable power tool of the gun type having a barrel portion accommodating a motor which may be a rotary air motor, a rotary electric motor, or a reciprocating motor, means for securing a chuck at the front end of said barrel portion, a handle portion extending downwardly and rearwardly from said barrel portion at an obtuse angle, and a projecting wing at each side of said barrel portion extending longitudinally of said barrel portion to form a rest or support for the thumb and forefinger and means for separating said thumb and forefinger from the other fingers of a hand grasping the rear end of the barrel portion and the handle portion, said barrel portion forming a ridge separating said thumb and forefinger. In pneumatic tools of this type we provide a noise damping chamber in said barrel portion, and exhaust pas-

sages in said projecting wings leading from said damping chamber to the atmosphere and opening at the forward ends of said wings. Other features of the invention will appear from the following description of a preferred embodiment of the invention selected for the purpose of illustration only and which should not be considered to limit the invention, the scope of which is set forth in the appended claims.

In the drawing, FIG. 1 is a perspective rear and side view of a pneumatic drill embodying to the invention. FIG. 2 is a front view of the drill illustrated in FIG. 1. FIG. 3 is a perspective plan view of the drill in slightly depressed position. FIG. 4 is a longitudinal section of the drill illustrated in FIGS. 1 and 3 on lines IV—IV in FIG. 2. FIG. 5 is a section on lines V—V. FIG. 6 a section on lines VI—VI, and FIG. 7 a section on lines VII—VII of FIG. 4. FIGS. 5—7 are on a reduced scale as compared with FIG. 4. FIG. 8 is a perspective view of a tool embodying the invention lying on a table and shows a hand about to grasp the tool.

The pneumatic drill illustrated in the drawing is provided with a body which may be cast from a suitable aluminum alloy, artificial resin, or other suitable material and which consists generally of a barrel portion 1 and a handle portion 2 extending downwardly and rearwardly from said barrel portion at an obtuse angle. The barrel portion 1 forms projecting wings 3, 4 at each side of the barrel portion extending longitudinally forwardly and separated by a ridge 5 so as to form between them upper concave portions 6 and 7, respectively, in which the forefinger 8 and the thumb 9 of a hand 10 holding the rear part of the barrel and the handle portion 2 of the tool may rest. At the rear end of the barrel 1 and the back of the handle portion 2 a curved portion 11 is formed which fits the palm and the heel of the hand and said portion 11 ends in a lip 12 at the upper end of the barrel. The portion 11 forms a large and broad surface against which the hand presses and which has so large an area that only a moderate pressure per square centimeter is produced. The wings 3 and 4 and the underside 13 of the barrel portion are formed rather flat so as to permit free motion of the middle finger 14 of the hand 10 so that said finger may be used to manipulate the trigger 15 disposed in the angle included between the barrel portion 1 and the handle portion 2 and having a rectilinear motion in the handle portion directed substantially towards the centre of the wrist of a hand holding the tool. While the thumb and forefinger, when the tool is grasped, guide the tool and hold it carefully in a desired direction, the manipulation of the trigger has no or very little tendency to change such direction. The tool is therefore very easy on the operator and causes but little fatigue even if it is used during long periods.

When the tool rests on a table the balance is such that the tool takes a slightly depressed position as is obvious from FIG. 8. It is therefore possible for the operator to get the correct grip on the tool immediately, and it is not necessary for him to change or adjust his grip before he starts to work with the tool, which reduces operating time.

Compressed air is supplied to the tool through a bushing 16 fitted in the lower end of the handle portion 2, and the supply to the motor is controlled by a valve 17 manipulated by means of the trigger 15. A chamber 18 in the handle may be used for providing a suitable lubricant which is conveyed to the compressed air inlet through a wick 19. In the illustrated embodiment 20 is a rotary air motor of the sliding vane type fitted in a bore 21 in the barrel portion 1. Two exhaust chambers 22, 23 surround the cylinder of the motor and communicate with each other through narrow spaces 33 and through restricted passages 24 with a second exhaust chamber 25.

in the barrel portion 1 which arrangements result in a considerable noise dampening effect on the exhaust from the motor. From the chamber 25 exhaust passages 26 in the wings 3, 4 convey the exhaust air to the atmosphere in a forward direction with respect of the tool so that the exhaust does not interfere with the hand 10 holding the tool.

A planetary reduction gear 27 is fitted in a gear casing 28 fitted in the forward end of the barrel 1, and 29 indicates a cap covering the front end of the gear casing. 30 is a tool spindle and 31 a chuck carried by said spindle in which a drill or other working implement may be fitted.

As is obvious from FIGS. 1-3, the hand 10 and the longitudinal axis 32 of the forearm are substantially in line with the feeding direction and rotary axis of the tool so that the hand is subjected to substantially no bending moment during the operation of the tool, and the manipulation of the trigger 15 by means of the finger 14 has no or very little tendency to change the direction of the tool. The tool is consequently very easy on the hand and causes very little fatigue in operation. The tool is also very easy to grasp when lying on a table as is obvious from FIG. 8, which shows a tool whose centre of gravity is in front of a vertical plane through the points of contact with the table on the wing 4 and the body so that the tool is at rest in a slightly depressed position. It should be observed also that the wings 3, 4 do not prevent the tool from entering a corner and consequently the wings do not increase the minimum distance between the tool axis and the surface 5 which defines how close to a wall or a corner the tool may be operated.

The above described tool is only an example and the invention may be modified in several ways within the scope of the claims.

What we claim is:

1. A portable power tool of the gun type having a barrel portion accommodating a motor and an implement-carrying chuck and a handle portion extending downwardly and rearwardly from said barrel portion at an obtuse angle, a projecting wing at each side of said barrel portion extending longitudinally of said barrel portion to form a rest or support for the thumb and forefinger of the hand of the operator grasping the tool and means for separating said thumb and forefinger from the other fingers of such hand grasping the rear end of the barrel portion and the handle portion of the tool, said barrel portion forming a ridge separating said thumb and forefinger, a noise dampening means in said barrel portion, and exhaust passages in said projecting wings leading from said dampening means to the atmosphere and opening at the forward ends of said wings.

2. A portable power tool as defined in claim 1 having a pneumatic motor disposed in said barrel portion, an air exhaust chamber in the barrel portion and the wings peripherally spaced with respect to said motor, a second exhaust chamber in the barrel and the wings in front of the motor, a restricted communication in the barrel portion between said chambers, and outlet passages in the wings from said second exhaust chamber.

3. A portable power tool of the gun type having a barrel portion accommodating a motor and an implement-carrying chuck and a handle portion extending downwardly and rearwardly from said barrel portion at an obtuse angle, a motor cylinder in said barrel portion arranged with its axis longitudinally of the axis of the barrel portion, a rotor in said cylinder mounted to rotate about an axis longitudinally of the axis of said barrel portion a projecting wing at each side of said barrel portion close to the bottom of the barrel portion extending longitudinally of the barrel portion to form a rest or support for the thumb and forefinger at the sides of the upper half of the cylinder and means for separating said thumb and forefinger from the other fingers of a hand holding said barrel and handle portions, said wings and the bot-

tom of the barrel portion forming a relatively flat underside, a comparatively broad pressure surface at the upper rear side of said handle portion, merging into a ridge directed upwardly and rearwardly, said pressure surface fitting the palm of a hand holding said tool for exerting pressure on the tool longitudinally of the axis of the barrel portion, and a trigger having a rectilinear movement substantially towards the centre of the wrist of said hand and situated just below said underside for controlling said motor by means of the middle finger of said hand holding the tool.

4. A portable power tool of the gun type having a barrel portion accommodating a rotary pneumatic motor and an implement-carrying chuck and a handle portion extending downwardly and rearwardly from said barrel portion at an obtuse angle, a ridge formed by the upper part of said barrel portion to fit between the thumb and the forefinger of a hand holding said tool, a projecting wing at each side of said barrel portion close to the bottom of the barrel portion extending longitudinally of the barrel portion at the sides thereof to form a rest or support for the thumb and forefinger and means for holding apart said thumb and forefinger from the other fingers of a hand holding said barrel and handle portions, said wings being widest at the front end of the barrel portion and tapering rearwardly and forming together with said ridge two longitudinal grooves or depressions of smooth shape for accommodating the thumb and the forefinger of said hand, air exhaust passages from said motor in said wings, air exhaust ports in the front faces of the wings, and a trigger below said barrel portion movable close to the underside of the barrel portion and wings towards the handle portion for manipulating said air motor by means of the middle finger of said hand holding the tool.

5. A portable power operated tool of the gun type having a barrel portion accommodating a rotary motor and an implement-carry chuck and a handle portion extending downwardly and rearwardly from said barrel portion at an obtuse angle, a motor cylinder in said barrel portion arranged with its axis longitudinally of the axis of said barrel portion, a rotor in said cylinder mounted to rotate about an axis longitudinally of the axis of said barrel portion a projecting wing at each side of said barrel portion close to the bottom of the barrel portion extending longitudinally of the barrel portion to form a rest or support for the thumb and forefinger at the sides of the upper half of the cylinder of a hand holding said barrel and handle portions and said wings being ridge-shaped and extending laterally of said barrel portion substantially at the handle side of said rotor axis, and a planetary reduction gear at the forward end of the barrel portion coaxially with said motor for reducing the speed of the motor to the working speed of the chuck, and a trigger below said barrel portion movable close to the underside of the barrel portion and wings towards the handle portion for manipulating said motor, said rotary motor, said chuck and said planetary gear having a common rotary axis.

6. A portable power operated tool of the gun type having a barrel portion accommodating a rotary motor, a chuck-carrying spindle at the front end of said barrel portion coaxial with said rotary motor, a driving gear transmission in the forward portion of the barrel portion forming a driving connection between said motor and said spindle, a handle portion extending downwardly and rearwardly from said barrel portion at an obtuse angle, a motor cylinder in said barrel portion arranged with its axis longitudinally of the axis of said barrel portion, a rotor in said cylinder mounted to rotate about an axis longitudinally of the axis of said barrel portion a comparatively broad pressure surface at the upper rear side of said handle portion merging into a ridge directed upwardly and rearwardly, said pressure surface fitting the palm of a hand holding said tool, a projecting wing at

each side of said barrel portion close to the bottom of the barrel portion extending longitudinally of the barrel portion to form a rest or support for the thumb and forefinger of said hand at the sides of the upper half of the cylinder and a means for holding apart said thumb and forefinger from the other fingers of the hand holding said barrel and handle portions, and a trigger close below said barrel portion and said wings being ridge-shaped and extending laterally of said barrel portion substantially at the handle side of said rotor axis for manipulating said motor.

7. A portable power tool of the gun type having a generally cylindrical barrel portion accommodating a motor having a rotor coaxial with said barrel portion and a handle portion extending downwardly and rearwardly from said barrel portion at an obtuse angle, laterally projecting wings extending longitudinally of said barrel portion at each side thereof, said wings providing with the upper part of said barrel portion concavely rounded and substantially parallel groove-like portions at the bases 15 20

of the upper sides of the wings for supporting the thumb and forefinger of a hand holding the tool.

8. A tool as defined in claim 7, in which the shaft of said rotor carries an implement-carrying chuck coaxial with the rotor, said groove-like portions of said barrel portion being substantially parallel and coplanar in a plane substantially coincident with the axis of said chuck, whereby the plane passing through the thumb and forefinger of a hand grasping the tool in intended fashion is coincident with or closely adjacent to the axis of said rotor and said chuck, to thereby provide for optimum guidance and application of longitudinally exerted force on the implement operated by the tool, by the hand of the operator.
